LOOM TEMPLE

Joseph Gilpin, Central Falls, R. I.

Application January 13, 1933. Serial No. 651,596

3 Claims. (Cl. 139—295)

My invention broadly relates to improving the cloth tensioning function of the Dutcher type loom temple as exemplified in the Dutcher, Re-issue Patent No. 6,831 or the Stimpson Patent No. 543,788. Due to the fact that temples of this class generally have a predetermined and fixed cloth receiving space between the cap and the roll or rolls, it has been found that cloths of greater thickness have a greater frictional engagement than those of thin construction with the result that it was necessary to change the entire temple or at least substitute rolls of different surface characteristics when the loom was changed from weaving one class of goods to another. My temple because of the inclusion in the cap construction of a vertically adjustable cloth tensioning bar enables any set of temples to be used in the weaving of goods of great variety with merely adjustment of the said tensioning bar.

Furthermore it has been found possible to eliminate the "marking" of light fragile goods as silk or rayon by the toothed rolls which it was found necessary to use in the old style temples to secure the proper lateral cloth tension.

In temples of the prior art it has been found that after continued use the cloth engaging rolls were worn so that they had to be renewed for proper lateral stretching of the cloth. With the use of the adjustable tensioning bar of my invention it is possible to continue in operation any one set of rolls from one quarter to one third longer than with the known temple caps.

In the accompanying drawing, Figure 1 is a plan view of the temple head of my improved device.

Figure 2 is a cross-section taken on the line 2—2 of Figure 1.

Figure 3 is a cross-section on line 3—3 of Figure 1, but showing a warpwise section of the cloth as it moves through the temple.

Figure 4 is a side view of the temple cap showing in dotted lines the groove for receiving the cloth tensioning bar and the screw holes through which the adjusting screws are passed.

The specific elements of the device as illustrated in the drawing and bearing corresponding reference numbers, are as follows: The usual spring pressed supporting bar is numbered 1 and carries the base 2 containing the cloth engaging rollers 3 rotatively mounted in bearings in said base. The cap 4 is securely fastened to the base 2 by a screw 10 at a sufficient distance to permit cloth of the maximum thickness to pass freely between the two as clearly shown in Figure 3.

In the prior art devices this space was in effect variable only within narrow limits by means of washers or packing between the shank of the cap and the base or by filing the cloth engaging edges of the cap, both with bad results in varying the tortuous path of the cloth and diminishing the wrapping of the cloth about the rolls.

As clearly shown in Figures 2 and 3 the cloth tensioning bar 6, which is approximately the same length as the rolls 3, is slidably mounted in a recess in the central ridge 5 of the cap 4 in parallel relation to the cloth rolls 3 and, if two such are used as in the illustrated example, vertically above the intervening space. The screws 7, 6 are threaded in the cap ridge 5 and their ends determine the uppermost position of the top of bar 6 while the screws 9 pass freely through the ridge and are threaded in the bar. By turning the screws 9 either right or left the bar 6 may be raised or lowered so as to place the edge 8 in proper relation to the cloth as shown in Figure 3. Once the proper position of the bar has been determined it can be securely locked by turning down the screws 7 into firm engagement with the top of the bar.

As clearly shown in Figure 3 the tapered edge portion 8 of the tensioning bar bears directly on the cloth and forces it to follow a tortuous course underneath the edges of the temple cap, over the rolls and under the edge of the bar. The extent of the bending of the cloth and wrapping thereof about the upper surfaces of the rolls is determinable by the vertical position of the bar 6 and in view of the ease of adjustment it is possible to locate the bar at the required height for firmly and correctly tensioning cloth of any weight or texture.

Inasmuch as the proper tensioning of the cloth as woven is an important and essential element of good weaving, my invention in its results of full and correct lateral tensioning of cloth of any quality and at all times is a substantial improvement over the prior art. As there are many possible changes of elements of my device as illustrated, for example in using one or three rolls instead of two or varying their position which are within the scope of my invention I wish it to be limited only by the terms of the appended claims.

I claim:

1. In a loom temple the combination of a base, rolls rotatively supported thereby, a cap having a recess extending longitudinally for the greater part of the length thereof, a bar having a straight narrow cloth-engaging edge normally fixed in

- said recess but adapted to be adjusted vertically to different positions therein so as to vary the tortuous course of the cloth between the rolls and the lower edge of the bar.
- 5 2. A loom temple having rotatable lower rolls and a longitudinally recessed cap in combination with an upper cloth engaging bar tapered to a straight, smooth lower edge, said bar adapted to be vertically adjusted in the cap recess so that 10 the lower edge thereof may be fixed for operation in any desired position in the middle vertical plane between the rotatable rolls and below the plane tangent to the upper surfaces of both rolls for the purpose of determining the sinuosity of 15 the cloth selvage passing between the rolls and the bar.
3. A loom temple head having a base and cloth engaging rolls rotatably supported thereon in

combination with a cap fixed to the base, an enlarged central ridge portion on said cap containing a rectangular recess extending in parallelism with said rolls, and a cloth engaging bar having a substantially rectangular body portion 80 slidably mounted in said recess so as to be vertically movable, said bar having a lower tapered cloth engaging portion, and means to vary the vertical position of the bar so as to locate the cloth engaging edge of the tapered portion between the rolls and below the plane tangent to their upper surfaces thus in operation serving to bend the passing cloth about the rolls to a greater or lesser degree to vary the frictional engagement of the cloth with the rolls and thereby 85 provide correct lateral cloth tensioning. 90
